TIMING DEVICE

Fritz Loewenstein, Newport, Del., assignor to J. E. Workman, Inc., a corporation of Delaware

Application January 29, 1948, Serial No. 4,991

6 Claims. (Cl. 161—1)

1

This invention relates to a timing device and more particularly to an automatic device having a plurality of switches which may be actuated in any desired order and after any desired time delay.

There are many industrial operations which require a succession of steps to be performed in a certain order and for definite periods of time. Innumerable machines and processes are now controlled manually for lack of a practical automatic control device. It is, therefore, the principal object of this invention to provide a timing device for automatically actuating a plurality of control circuits.

It is another object to provide a timing device which is suitable for use on a great variety of machines and processes by reason of being easily adjustable as to time delays and sequences of operation.

It is a further object to provide a timing device that is inherently very accurate and stable in operation.

It is a further object to provide a timing device capable of providing both short and long time delays in the same cycle of operation.

In pursuance of these and many other objects which will be apparent to those skilled in the art, I provide a lead screw driven at constant speed by a motor, preferably a synchronous motor. A follower is slidably engaged with a guide bar disposed parallel with the lead screw. The follower is pivotable about the axis of the guide bar into engagement with the threads on one side of the lead screw. When engaged with the lead screw threads, the follower is driven along the lead screw at a constant speed determined by the pitch of the threads and the speed of rotation of the screw. A plurality of fingers projecting from the follower are operative to actuate a plurality of switches disposed along the path of travel. Means are provided for adjusting the positions of the individual switches thereby adjusting the time delay preceding their actuation. A limit switch actuated by the follower controls a solenoid which disengages the follower from the lead screw and allows it to return to the starting position for a new cycle of operation. In order to provide both long and short time delays in the same cycle of operation, the lead screw is driven by two synchronous motors, one being a low speed, and the other a high speed motor. One of the adjustable switches is then connected to control the motors so that the lead screw is first driven by one, and after a definite time delay, driven by the other motor.

2

Referring briefly to the drawings where I show one embodiment of the invention:

Figure 1 is a side elevational view of the device with the enclosure cut away to show the relationship of the elements;

Figure 2 is a horizontal sectional view taken on the line 2—2 of Figure 1 looking in the direction of the arrows, showing the means by which the follower engages and disengages the lead screw; and

Figure 3 is schematic wiring diagram illustrating a manner of connecting the electrical elements of the device.

Referring now in greater detail to the drawings, 15 lead screw 10 is journaled in bearings 11 supported by enclosure 12. Driving motors 15 and 16 have different synchronous speeds and have a disk 17 secured to their common shaft 18 by means of set screw 19. A beaded collar 20, 20 secured to lead screw 10 by means of set screw 21, is driven by the disk 17. The speed of rotation of lead screw 10 can be preset over a range of values by adjusting the position of collar 20' on the lead screw. When collar 20' is set closer 25 to the axis of disk 17, lead screw 10 rotates at a lower speed.

Motor 15 may be a high-speed motor, and motor 16, low-speed. When motor 15 is energized, it rotates at high speed and the rotor of motor 16, being on the same shaft and not energized, also rotates at high speed. As will be subsequently described, means are provided to then de-energize motor 15 and energize low-speed motor 16. In this way, lead screw 10 may be driven at high speed for a definite period of time and then driven at low speed for another period of time.

The motors 15 and 16 may be of the synchronous type so that the speed of rotation of lead screw 10 will be constant and accurately fixed by the particular motor energized. The motors may be of the reversible type for reasons that will be described.

A follower 20 is slidably engaged with polygonal 45 guide bar 21 which is rotatably mounted to the enclosure 12 at 22 and 23. A spring 24 biases the guide bar in the direction tending to hold follower 20 against lead screw 10. A post 25 extends laterally from guide bar 21 and the extremity of the post is connected through spring 26 to the armature 27 of solenoid 28. When solenoid 28 is energized, guide bar 21 is rotated against the effect of biasing spring 24 in a direction such that follower 20 is moved away from lead screw 10. Spring 26 is stiff and provides

positive, yet shock-absorbing, actuation of the guide bar.

The portion of the follower 20 which engages with lead screw 10 is in the nature of a half nut threaded to accommodate the threads on the lead screw. By this construction, the follower 20 can be readily engaged with, and disengaged from, the lead screw 10. A finger plate 30 is rigidly secured to the follower 20 and is provided with a plurality of fingers 31 extending on lines radial from the axis of guide bar 21, as shown to advantage in Figure 2. The fingers 31 are operative to actuate a plurality of switches 32 which are disposed in an arcuate formation, there being one switch 32 for each finger 31. The switches 32 are each in threaded engagement with a positioning screw 33. The positioning screws 33 are journaled at their ends 34 and 35 in the enclosure 12. Each positioning screw 33 is provided with a bevel gear 36, which is engaged by a mating bevel gear 37 controlled by knob 38 disposed on the exterior of the enclosure 12. By turning knob 38 the corresponding switch 32 may be positioned anywhere along the corresponding positioning screw 33. A rod 39 is provided in parallel relationship with each positioning screw 33 and is operative to be slidably engaged by a groove 40 in each switch. Rods 39 prevent rotation of switches 32 about the corresponding positioning screws.

It is to be noted that when follower 20 is in engagement with lead screw 10, all fingers 31 are lined up with the actuating buttons 42 of switches 32. However, when follower 20 is disengaged from lead screw 10, fingers 31 are displaced from their original position in such a way that they cannot engage the actuating buttons 42. This structure is provided so that when the follower 20 is engaged with the lead screw and is traveling therewith, the fingers 31 will actuate the switches 32. Then when the follower 20 is disengaged from the lead screw and the follower drops to its original position, the fingers will not engage the actuating buttons 42 of the switches 32.

The starting or zero position of the follower 20 is at the bottom of lead screw 10. The portion of follower 20 which circumscribes the guide bar 21 is cut away at 44 so that post 25 will not interfere with follower 20 when the follower is in its zero position. When in the zero position, follower 20 is in engagement with actuating button 47 of limit switch 48. When follower 20 reaches the top end of lead screw 10, it engages and operates the actuating button 49 of top limit switch 50. It is to be understood that the functions of limit switches 48 and 50 may be performed by two of switches 32 disposed in corresponding positions at the bottom and top of their respective positioning screws 33. It is apparent that the device is thus adaptable to a great variety of applications and modes of operation.

The bottom limit switch 48 (or a switch 32 used in place thereof) may be of the normally closed type. The top limit switch 50 may be of the normally open type illustrated in Figure 3, having a holding solenoid 51. As shown in Figure 3, electricity is supplied from source 55 to actuating solenoid 28 under the control of limit switches 48, 50 and manually operated switch 56. Source 55 also provides energy for motors 15 and 16 under the control of single pole, double throw switch 57.

The operation of the timing device will now be described starting with the follower 20 in the in-

termediate position shown in Figure 1. Follower 20 is in engagement with the threads of lead screw 10 and is moved upwardly at a constant speed. As the fingers 31 move past the switches 32, the latter are actuated by the corresponding fingers. The switches 32 will be operative to control whatever machine or process the timing device is used with. When the follower 20 arrives at the top of lead screw 10, the follower will depress actuating button 49 of top limit switch 50. It will be seen by reference to Figure 3, that under these conditions electricity is allowed to flow from source 55 through wire 60, armature 61 of limit switch 50, wire 62 through solenoid 28 and back to the source 55. Electricity also flows through wire 60, armature 61, holding solenoid 51, wire 64, lower limit switch 48 and back to the source 55. When current flows through solenoid 28, the solenoid is energized, drawing its armature 27 inwardly and acting through spring 26 and post 25 to rotate guide bar 21. The guide bar, being of polygonal shape, causes follower 20 to be disengaged from the lead screw 10. When thus disengaged, the follower 20 is free to drop to the initial position at the bottom of the lead screw. It is apparent from Figure 2 that when follower 20 pivots about the axis of guide bar 20, fingers 31 are displaced to a position such that they are not in line with and cannot actuate the buttons 42 of switches 32. Therefore, when follower 20 drops to the initial position, the fingers 31 do not actuate switches 32.

When the follower 20 reaches the bottom or initial position, it hits actuating button 47 of bottom limit switch 48 thereby opening switch 48. During the time that follower 20 is dropping from the top position, holding solenoid 51 is operative to keep top limit switch 50 closed, thereby maintaining follower 20 out of engagement with lead screw 10. Then when follower 20 reaches the bottom and opens limit switch 48, the energy to the holding solenoid 51 is interrupted and armature 61 of limit switch 50 is allowed to return to its normally open position. Solenoid 28 is thus de-energized and spring 24 on guide bar 21 returns follower 20 to a position in engagement with the lead screw 10. Follower 20 then moves longitudinally up the lead screw 10 and the fingers actuate the switches 32 in the pre-set order and with the pre-set time delay. It is thus apparent that the cycle of operation may be automatically repeated over and over. In the event it is desired to return the follower 20 to its initial position and temporarily keep it there, switch 56 may be closed manually. Solenoid 28 then holds follower 20 out of engagement with lead screw 10.

Switch 57 is provided so that either high speed motor 15 or low speed motor 16 may be employed at the will of the operator. If it is desired to use a cycle of operation including a short time delay and subsequently a long time delay, switch 57 may be one of the adjustable switches 32. In the operation of the device under these conditions, lead screw 10 may be driven by high speed motor 15 from the time follower 20 is at the initial position until it reaches an intermediate position where a finger 31 actuates switch 57, de-energizing motor 15 and energizing motor 16. For the balance of the cycle, lead screw 10 will rotate slowly and follower 20 will move at a correspondingly low rate. In this way, it is possible to obtain time relays in the order of fractions of a second and hours in the same cycle of operation.

Another mode of operation, also within the con-

temption of the invention, may be obtained where one or both of the motors 15 and 16 are reversible. In this event, limit switch 50 or one of switches 32 may be connected so as to reverse the direction of rotation of a motor instead of energizing solenoid 28. Then when the switch is actuated, follower 20 will be driven down lead screw 10 instead of dropping down by gravity. Under this mode of operation, fingers 31 may engage and actuate the switches 32 on the way down as well as on the way up, or fingers 31 may be provided with pawls which actuate switches 32 on the way up but not on the way down.

While I have shown and described only one embodiment of my invention, it is to be understood that I am not to be limited thereto and that changes may be made in the invention without departing from the spirit and scope of the claims.

I claim:

1. An electric timing device comprising a lead screw and driving means therefor, a follower engageable with the lead screw for longitudinal movement therealong, a plurality of fingers extending from the follower, and a plurality of switches disposed in the path of said fingers when the follower is engaged with the lead screw, the switches not being in the path of said fingers when the follower is disengaged from the lead screw.

2. An electric timing device comprising a lead screw and driving means therefor, a guide bar parallel with the lead screw, a follower in slideable engagement with the guide bar and pivotable about the axis of the guide bar into engagement with the lead screw for longitudinal movement therealong, solenoid means for pivoting the follower into and out of engagement with the lead screw, a plurality of fingers extending from the follower, and a corresponding plurality of switches operatively disposed in the path the fingers take when the follower is engaged with the lead screw, but not in the path the fingers take when the follower is disengaged.

3. In an electric timing device, a lead screw and driving means therefor, a follower engageable with the lead screw for longitudinal movement therealong from an initial position, a limit switch disposed in the path of the follower for actuation thereby, solenoid means operative responsive to said limit switch to disengage the follower from the lead screw and allow it to re-

turn to its initial position, and a second limit switch at the initial position operative responsive to return of the follower to control the solenoid and thereby re-engage the follower with the lead screw, whereby the cycle is repeated.

4. In an electric timing device, a substantially vertical lead screw and driving means therefor, a follower engageable with the lead screw for upward movement therealong, a limit switch disposed in the path of the follower for actuation thereby, solenoid means operative responsive to said limit switch to disengage the follower and allow it to fall to its initial position, and a second limit switch at the initial position, the solenoid means being operative responsive to the second limit switch to re-engage the follower with the lead screw.

5. In an electric timing device, a lead screw and a plurality of driving motors therefor, a common shaft connecting said motors, means secured to the common shaft for driving the lead screw, a follower engageable with the lead screw for longitudinal movement along the screw, and a switch disposed to be actuated by the follower during longitudinal movement thereof, the switch being operative to de-energize one of the driving motors and energize another.

6. An electric timing device for controlling a plurality of circuits in a pre-set sequence after pre-set time delays, comprising a lead screw and a driving means therefor, a follower engageable with the lead screw, a guide bar parallel to the lead screw about the axis of which bar the follower pivots into engagement with the lead screw, and a plurality of switches disposed in the path of the follower and actuated thereby, the switches being arranged to be actuated in a pre-set sequence after pre-set time delays.
